H. H. EATON.

OPERATOR'S CHAIR.

APPLICATION FILED FEB. 4, 1918.

1,318,437.

Patented Oct. 14, 1919.

INVENTOR.

Harrison H. Eaton
By his Attorney,
Nelson W. Howard

UNITED STATES PATENT OFFICE.

HARRISON H. EATON, OF BEVERLY, MASSACHUSETTS, ASSIGNOR TO UNITED SHOE MACHINERY CORPORATION, OF PATERSON, NEW JERSEY, A CORPORATION OF NEW JERSEY.

OPERATOR'S CHAIR.

1,318,437.

Specification of Letters Patent.

Patented Oct. 14, 1919.

Application filed February 4, 1918. Serial No. 215,318.

To all whom it may concern:

Be it known that I, HARRISON H. EATON, a citizen of the United States, residing at Beverly, in the county of Essex and State 5 of Massachusetts, have invented certain Improvements in Operators' Chairs, of which the following description, in connection with the accompanying drawings, is a specification, like reference characters on the drawings indicating like parts in the several figures.

This invention relates to chairs. The invention is illustrated as embodied in a folding chair especially designed for the use of 15 machine operators.

The invention aims generally to produce a chair which, while inexpensive, will be more durable and safer than chairs of this type now generally used and which will still be 20 convenient and comfortable for the operator.

Another object of the invention is to provide a chair of the general type referred to, which, without sacrifice of other advantages, will be so constructed and arranged as 25 to avoid objectionable blocking of or encroachment upon factory aisle space.

The illustrated construction and arrangement requires only a minimum of aisle space when the chair is occupied, thus facilitating 30 keeping the factory aisles clear, and at the same time is such that whenever the occupant leaves the chair, without special attention on the part of the occupant, the chair immediately assumes a position such as materially to increase the aisle space, thereby 35 facilitating aisle movements either of factory employees or of merchandise. This last-named characteristic is of conspicuous value in the event of any sudden emergency resulting in a general exodus of employees, 40 particularly in case of panic from fire or other cause.

With this object in view, an important 45 feature of the invention consists in providing a chair which can be secured to the floor in proper position relatively to the bench and which, when unoccupied, will assume a position immediately adjacent to the bench, preferably so that the seat will be partially 50 under the bench and the back partially over it. In order that the rear legs of a chair so placed will not project into the aisle, another feature of the invention consists in providing means for causing the rear legs 55 normally to approach the front legs and as-

sume a substantially vertical position near the bench and thus leave the aisle clear when the chair is unoccupied.

Other objects and features of the invention will be apparent when the following 60 description and claims are considered in connection with the accompanying drawings.

In the drawings:

Figure 1 shows, in full lines, a side elevation of the chair in position to be occupied 65 and also shows, in dotted lines, the chair tipped forward with the rear legs folded up toward the front legs;

Fig. 2 is a rear elevation of the chair in the position indicated in full lines in Fig. 1;

Fig. 3 is a cross section of the back showing the means for securing the back-rest in adjusted position; and

Fig. 4 is a detail of the base showing, in cross section, the means provided for adjusting the chair either toward or from the 75 bench.

Referring to the drawings in detail, 10 is the frame having front legs 12 and a back 14 projecting therefrom. This frame, including the extensions, is made, in the preferred construction, of angle iron or other suitable structural material bent at a plurality of points to give it the desired shape and, for convenience in manufacture, is made 80 of two similar but oppositely shaped pieces secured together at the top by means of the plate 16 and rivets 18. The front legs are pivotally supported to the base 20, the pivots being shown at 22. When in position for 85 occupancy, the frame is supported by the rear legs 24 pivotally connected to the frame at 26. The upper portion of the rear legs forms one member of a toggle and a connecting rod 28, pivotally connected to the rear 90 legs at 30 and to the base at 32, forms the other member of the toggle. This toggle, when straightened, will cause the chair to pivot about the pivots 22 and move forward into the dotted line position shown in Fig. 100 1; at the same time the rear legs 24 approach the front legs so as to clear the aisle for the purpose specified. A spring 34 secured at one end to the frame and at the other end to the rear legs causes the toggle to 105 straighten and the chair to assume the folded position when the occupant rises from the chair. The base 20 is composed of two members 20^a and 20^b, the member 20^a being secured to the floor and the member 110

20^b being mounted upon the member 20^a for adjustment toward and from the bench, being locked in position by the bolt 36 and wing nut 38, as shown in Fig. 4.

5 In the construction shown in the drawings, a seat 40 is secured to the frame 10 by means of two pieces of angle iron 42 bent as shown, and by a plurality of suitable fasteners 44 and 46, the seat 40 being secured to the angle irons 42 in any suitable manner.

10 The seat and frame are constructed and arranged to be secured together in any one of a plurality of relative locations in order 15 to provide a vertical adjustment of the seat.

15 A plurality of holes 48 are made in the extension 14 of the frame, and corresponding holes 50 are made in the extensions 12 forming the front legs. The fasteners 44 and 46 20 pass through holes in the ends of the angle irons 42 and through any selected set of holes 48 and 50 to adjust the seat to the desired height.

25 To the extension 14 which forms the back of the chair, a back rest 52 is adjustably secured by the clamping plate 54, the bolts 56 and wing nuts 58, as shown in Fig. 3.

30 Having thus described the invention, what is claimed as new and desired to be secured by Letters Patent of the United States is:—

35 1. A folding chair having, in combination, a frame, front legs fixedly projecting from the frame, supporting means to which the front legs are pivoted, rear legs pivotally connected to the frame, a pivotal connection between said supporting means and the rear legs, and a seat carried by the frame.

40 2. A folding chair having, in combination, a frame, front legs fixedly projecting from the frame, supporting means to which the front legs are pivoted, rear legs pivotally connected to the frame, means for causing the rear legs normally to approach the front legs, and a seat carried by the frame.

45 3. A folding chair having, in combination, a base, a frame having extensions forming front legs pivotally connected to the base, rear legs pivotally connected to the frame, a connecting rod pivotally connected 50 to the base and the rear legs, means for causing the rear legs normally to approach the front legs, and a seat carried by the frame in fixed relation thereto.

55 4. A folding chair, having, in combination, a frame, front legs projecting from the frame, supporting means to which the front legs are pivoted, rear legs pivotally connected to the frame, a toggle, means for

straightening the toggle to tip the chair forward when the occupant arises therefrom, 60 and a seat carried by the frame in fixed relation to the front legs.

5. A folding chair, having, in combination, a base, a frame having extensions forming front legs pivotally connected to the 65 base, rear legs pivotally connected to the frame and forming one member of a toggle, a second toggle member connected to the rear legs and to the base, means for causing the toggle formed by said members to become 70 straightened, and a seat carried by the frame in fixed relation to the front legs.

6. A folding chair, having, in combination, a frame composed of structural metal bent at a plurality of points to form the 75 front legs, seat support and back of the chair, supporting means to which said front legs are pivoted, rear legs pivotally connected to said frame and a seat carried by the frame.

80 7. A folding chair, having, in combination, a frame composed of structural metal bent at a plurality of points to form the front legs, seat support and back rest of the chair, supporting means to which said front legs are pivoted, rear legs pivotally connected to said frame, a seat, a plurality of fasteners for securing the seat to the frame, the seat and frame being constructed and arranged to receive such fasteners in a plurality of relative locations.

85 8. A folding chair having, in combination, a T-slotted piece provided with means for securing it to a floor, a base portion, a slot in said base portion, means passing 90 through the T-slot and the slot in the base portion for clamping the base portion in adjusted location, a frame, front legs projecting from the frame and pivotally mounted on the base portion, rear legs pivotally 95 connected to said frame, and a seat carried by the frame in fixed relation to the front legs.

9. An adjustable base for a chair having, in combination, a T-slotted piece provided 100 with means for securing it to a floor, a base portion, a slot in said base portion, means passing through the T-slot and the slot in the base portion for clamping the base portion in adjusted location, and means 105 on the base portion for securing a chair thereto.

110 In testimony whereof I have signed my name to this specification.

HARRISON H. EATON.
